MATERNITY SKIRT

Marianne Goldring, New York, N.Y., assignor to Sears, Roebuck and Co., Chicago, Ill., a corporation of New York

Application October 3, 1957, Serial No. 688,006

3 Claims. (Cl. 2—211)

My invention pertains to a maternity skirt and has to do more particularly with a skirt of novel construction which is designed to provide adjustability in height as well as in width to accommodate changes in the figure of the wearer during the progress of pregnancy.

A particular object of my invention is to provide a garment of the type referred to which will accomplish the above mentioned objects without detracting from the appearance of slimness below the abdomen and without causing a rise of the skirt at the hemline, such as usually occurs in ordinary garments as a result of changes in the figure.

My principal objective is accomplished by providing in the front portion of the garment adjustability in both vertical and lateral directions. This adjustability is accomplished for a wide variety of variations in the girth of the figure, to keep pace with the natural changes therein. As a result it is possible for the wearer to maintain a relatively slim appearance below the abdomen and without causing a rise in the hemline.

My invention will best be understood from the appended drawings illustrating a preferred embodiment thereof, wherein

Fig. 1 is a front elevational view of a skirt embodying my invention as worn during an early stage of pregnancy;

Fig. 2 is a side elevational view of the same;

Fig. 3 is a back elevational view of the same;

Fig. 4 is a front elevational view of the same skirt as worn during a later stage of pregnancy;

Fig. 5 is a side elevational view of the same as shown in Fig. 4;

Fig. 6 is a rear perspective view of the skirt as shown in Figs. 1-5, inclusive;

Fig. 7 is a front perspective view of the skirt as shown in Figs. 4 and 5, and

Fig. 8 is an exploded plan view of the pattern for the various panels comprising the skirt.

Referring first to Fig. 8, my improved skirt is preferably cut in a plurality of vertical elongated panels, viz: a more or less rectangular front panel *a* having secured to the top side edges thereof a pair of vertically spaced loops *12*. Secured to the sides of front panel *a* are side panels *b*, *b'* which are substantially identical in contour, but reversed on a vertical axis. These panels are roughly rectangular except that the length thereof from top to bottom slopes upwardly from the rear edge *13* to the front edge *14*. Thus, the top edge *15* of the side panels is higher toward the front and of substantially the same length as the front panel at the point where the side panels meet the front panel. It will also be seen that the vertical edge *14* of this panel is bias-cut in the upper portion thereof as indicated by the line *16* to provide a gore *17*, which is available for gradual expansion as the need arises.

A flexible tie member such as a tape or belt *20* is secured to the upper hem or marginal portion of side

panels *b*, *b'* as at *18* for purposes which will herein-after be described. Rear panels *c*, *c'* are likewise roughly rectangular and identical in contour, being likewise reversed in position on a vertical axis. The side edge *22* of each back panel is of substantially the same length as edge *13* of its adjacent side panel and the top marginal edge *24* of each back panel slopes downwardly toward the rear center edge *27*.

A V-shaped dart *30* is provided at the top of each of the rear panels *c*, *c'* between the side edges of said panels, said darts when taken in and stitched causing median edges *27* to slope toward the side and allow for shaping over the hips, as seen by dash line *19*. Adjacent the forward portion of each dart and at the top edge of the panel is provided a loop *32*.

At the bottom rear edge of each back panel *c*, *c'* is provided an elongated extension *35* whereby, when the panels are sewn together in the usual manner, a pleat *37* is formed (Fig. 6) to provide extra width at the bottom for walking.

The panels shown in Fig. 8, as described above, are stitched together along their side edges to provide the skirt shown in Figs. 1-7 inclusive. It will be noted that the bottom hemline is even all around, and remains so when worn, at all stages of pregnancy.

In the early stages of pregnancy the skirt will be worn in the manner shown in Figs. 1-3, inclusive. During this period, with the wearer's abdomen relatively flat, the tie members *20* will be drawn forwardly and through the lower loops *12* and thence rearwardly through the loops *32*. Each tie member may be secured as by a bow or the like at the appropriate rear loop *32*. At this stage the gore *17* will be fully folded in as seen dotted in Fig. 1, creating a softly pleated waistline. When worn in this manner, the excess material of the front panel extending between the lowermost of the loops *12* and the top margin extends neatly above the waist, as seen best in Figs. 1, 2 and 7.

During the latter stages of pregnancy, when the wearer's torso is of increased girth, the tie members *20* will be drawn through the upper pair of loops *12*, as seen in Figs. 4 and 5, thus allowing the additional material provided at the top of the front panel as well as the extended material of gores *17* to be draped gracefully over the growing abdomen and permitting the lower portions of the skirt to assume the same positions as when the figure was normal, with an even hemline. During this period the rear loops *32* need not be used and the ties *20* may be secured to the loops *12*.

Thus, it will be seen that my improved maternity skirt provides a neat and tailored appearance to the pregnant figure which is attractive and flattering. The flexible tie members *20* may be secured in an infinite number of positions and thus the garment may be adjusted to accommodate itself attractively and comfortably to the figure at all stages of pregnancy.

Various changes and modifications coming within the spirit of my invention may suggest themselves to those skilled in the art and hence I do not wish to be limited to the specific form shown or uses mentioned, except to the extent indicated in the appended claims.

I claim:

1. A maternity skirt comprising front, side and rear portions and having a substantially even bottom hemline and a top marginal portion adjacent the waistline, said marginal portion being higher in the front than in the back and side portions, said skirt having a pair of spaced extensible bores disposed in the top portion thereof and provided with a fold line at each lateral side of said front portion, elongated flexible tie means attached adjacent the top marginal portion of the skirt

remotely from the front and provided with a pair of free ends extending toward the front portion thereof, a plurality of vertically spaced tie engaging members disposed laterally of the front top marginal portion at said fold lines, said members being adapted to engage and retain said tie means at a plurality of points on the latter, whereby said tie means may engage a lower one of said tie engaging members and said gores be folded in in the early stages of pregnancy to accommodate the skirt to the relatively normal figure, the front portion of said skirt being disposed entirely outside the skirt when said gores are folded in, and the ties being engageable with an upper one of said members and said gores being more or less extendable during the latter stages of pregnancy, to accommodate the skirt to the increasing girth of the figure.

2. A garment as defined in claim 1 wherein the tie engaging members consist of loops through which the ties extend.

3. A garment as defined in claim 1 formed from front, side and rear panels which are vertically elongated and more or less rectangular in shape and are secured together along their side edges, said gores being provided by means of substantially triangular extensions disposed between the front and side panels, the vertical length of said panels varying between a maximum in the front panel and a minimum in the rear, and said panels being so secured along their vertical edges as to provide an even hemline at the bottom thereof and a gradual rise toward the front panel.
